HYPNOTIC COMPOSITION COMPRISING A BARBITURATE AND β,β -METHYL ETHYL GLUTARIMIDE

Robert Grenville Smith, Croydon, Victoria, Australia, assignor to Nicholas Proprietary Limited, Melbourne, Victoria, Australia, a company of Victoria

No Drawing. Application April 17, 1956
Serial No. 578,575

Claims priority, application Australia April 20, 1955

4 Claims. (Cl. 167—52)

This invention relates to barbiturate pharmaceutical preparations, for example, tablets, capsules, elixirs, suspensions and the like, containing barbiturates.

The barbiturates comprise an important and valuable group of central nervous system depressants frequently prescribed by physicians and widely used by the laity. Reference to this appears in the textbook entitled, "The Pharmacological Basis of Therapeutics," by Goodman and Gilman, page 126, published 1941 by the Macmillan Company, New York, U. S. A. The barbiturates are used medically for several purposes, the most important of which are for producing sleep, inhibiting convulsions, anaesthesia, and sedation. The general properties of barbiturates are possessed in varying degrees by individual members of the group and this has led to a large number of different compounds being employed in medicine. Some are long acting, others intermediate and still others very short acting. Administration may be oral or parenteral, but much more frequently the former.

Chemically, the barbiturates are derivatives of barbituric acid, having the general structural formula as follows:

wherein one or both of the hydrogen atoms attached to the carbon atom numbered 5 or the hydrogen atom attached to the nitrogen atom numbered 3 are replaced by another group to produce a compound having special property in the field. Examples are diethyl barbituric acid or barbital, phenylethyl-barbituric acid or phenobarbital, and 5-phenyl-5-ethyl-3-methyl barbituric acid or methyl-phenobarbitone. Salts of these compounds can be formed and are often employed, e. g. sodium ethyl (1-methyl butyl) barbiturate or pento-barbital sodium.

The wide use of the barbiturates has resulted in many cases of overdosage, either accidental or suicidal. This overdosage has frequently ended fatally. An authoritative review of the current usage of barbiturates in suicide and accidental death due to barbiturate poisoning in England has appeared in Lancet, January 21, 1956 at page 150. This paper estimates that between 80,000 and 100,000 lbs. of barbiturates are prescribed annually in the United Kingdom. Approximately 9% of all prescriptions under the National Health Scheme in the United

2

Kingdom were for barbiturates or preparations containing barbiturates. 6.4% of all prescriptions under the National Health Scheme in the United Kingdom in October 1954 contained barbiturates as the sole or principal therapeutic agent.

Since 1949 barbiturate poisoning in general has increased tremendously. The number of patients treated for barbiturate poisoning in England and Wales was 2800 in 1949; 3950 in 1951; and 4200 in 1953. Suicidal and accidental deaths from barbiturates have increased even more spectacularly. In 1946 the number of suicides was 78 and accidental deaths was 54, totalling 132; whilst in 1954 the suicides numbered 391 and accidental deaths 181, totalling 575. Since 1945 the total suicide rate from all agents has tended to oscillate but does not show a significant upward trend. Suicides from barbiturates, however, have increased approximately six times and it has been concluded that a preference has been shown lately for using barbiturates as suicidal agents rather than some other lethal means.

Research has recently disclosed a substance which exhibits outstanding antagonism towards barbiturates. This barbiturate antagonist is β,β -methyl ethyl glutarimide, having the structural formula as follows:

The above identified glutarimide is outstanding for the purpose of treating barbiturate poisoning, and, unlike other aneupatics used in the treatment of barbiturate poisoning, appears to be a closer approach than hitherto to a true barbiturate antagonist. This has been shown to be the case with animal experiments and has since been confirmed clinically with success in curing many cases of barbiturate poisoning in humans both in Australia and England.

The discovery has now been made that barbiturate poisoning can be prevented, rather than cured, by employing as a source of barbiturate a pharmaceutical preparation comprising a barbiturate and essentially a proportion of β,β -methyl ethyl glutarimide, insufficient to interfere with a therapeutic dose of barbiturate but sufficient to overcome the toxic effect of overdose. Thus, it is possible to make the barbiturates commonly used in general medical practice much safer by removing the risk of coma which follows ingestion of high doses at present. By combining with the barbiturate a proportion of β,β -methyl ethyl glutarimide such that the effectiveness of the barbiturate at normal dosages is unimpaired but at high dosage levels approaching the usual coma dose, vital body functions are maintained—the usual depressive toxic effects of the barbiturate on such functions as pulse rate, blood pressure, and the like are reduced to a safe level. In this way it is possible to protect patients from accidental or deliberate overdosage of barbiturate.

Clinical trials have shown that β,β -methyl ethyl glutarimide may be present in the pharmaceutical preparation in a proportion of 5% to 30% by weight of the barbiturate without interfering with the therapeutic effect of the barbiturate, to overcome the toxic effects of overdose. The β,β -methyl ethyl glutarimide is, in this way simultaneously ingested with the barbiturate to act as an

efficient antidote and prevent the toxic effect of an accidental or deliberate overdose of barbiturate.

In the clinical work 15%, 20%, 25% and 30% by weight of β,β -methyl ethyl glutarimide has been used. It is preferred to use 15% to 20% proportion of β,β -methyl ethyl glutarimide as this does not interfere with normal barbiturate effect at low dosages, but does satisfactorily prevent coma at high dosage levels. The overall useful proportion of β,β -methyl ethyl glutarimide can be expected to vary according to the circumstances of use.

Certain barbiturates, such as phenobarbitone, are prolonged in action; hence it is possible that the β,β -methyl ethyl glutarimide would be absorbed and perhaps excreted in some instances before being active. Because of this the pharmaceutical preparation of the invention may embody an agent delaying the release of the β,β -methyl ethyl glutarimide in the human gastro-intestinal tract. Thus, the preparation may comprise granules having insoluble coatings for delaying the absorption of the β,β -methyl ethyl glutarimide constituent of the mixture. Another procedure which may be employed consists in preparing multi-layer tablets in which a layer containing the barbiturate is compressed over a core containing the glutarimide, as hereinafter fully described in certain of the practical examples. Absorption rates (or release) of the drugs may thereby be artificially controlled, depending upon the rate of absorption, excretion and detoxication of the β,β -methyl ethyl glutarimide in relation to the barbiturate prescribed.

Pharmaceutical preparations in accordance with the invention may comprise, for example, any of the following medicinal barbiturates: Phenobarbitone (British Pharmacopoeia) or Phenobarbital (U. S. Pharmacopoeia); Amylobarbitone (British Pharmacopoeia) or Amobarbital (U. S. Pharmacopoeia); Butobarbitone (British Pharmacopoeia); Pentobarbitone Sodium (British Pharmacopoeia) or Pentobarbital Sodium (U. S. Pharmacopoeia); Quinalbarbitone Sodium (British Pharmacopoeia) or Secobarbital Sodium (U. S. Pharmacopoeia); and Hexobarbitone Sodium (British Pharmacopoeia) or Hexobarbital Sodium (U. S. National Formulary Vol. X, 1955).

Practical examples of pharmaceutical compositions in accordance with the invention are as follows, but it is to be understood that the invention is in no way limited thereto:

Example I

Tablets consisting of the following mixture were prepared:

	Grams
Phenobarbitone	30
β,β -methyl ethyl glutarimide	4.5
Lactose	100
Sucrose	50.5
Sodium carboxy methyl cellulose	10
Magnesium stearate (60 mesh)	5.0
	200

The phenobarbitone, β,β -methyl ethyl glutarimide, Lactose and sucrose all of 40 mesh size particles were mixed thoroughly in a blender, then massed by adding a mixture of equal parts of Industrial Spirit (alcohol 95%) and water. The moistened mass was passed through a 16 mesh sieve and granules dried at 50° C. The dried granules were passed through a 16 mesh sieve then mixed with sodium carboxy methyl cellulose (40 mesh size particles) and magnesium stearate (60 mesh size particles). Tablets were made $\frac{5}{16}$ " diameter, weighing 200 mgm., and containing 30 mgm. of phenobarbitone.

Example II

Tablets again were prepared consisting of the following:

	Grams
5 Pentobarbitone	60
β,β -methyl ethyl glutarimide	12
Lactose	78
Sucrose	35
10 Sodium carboxy methyl cellulose	10
Magnesium stearate	5
	200

15 The method of Example 1 was adopted, the pentobarbitone being of 40 mesh particles. Each 200 mgm. tablet contains 60 mgm. of pentobarbitone.

Example III

20 Capsules (hard gelatine) were prepared containing the following:

	Grams
Amylobarbitone	200
25 β,β -methyl ethyl glutarimide	25
Lactose	15
	240

30 Mix the constituents, each of which is of 40 mesh size particles and fill capsules of suitable size with 240 mgm. of the mixture. Each capsule will contain 200 mgm. amylobarbitone.

Example IV

35 An elixir was prepared consisting of the following:

Phenobarbitone	grams	4.00
β,β -methyl ethyl glutarimide	do	0.400
40 Tartrazine	do	0.100
Orange oil	ml	2.5
Alcohol 95%	ml	150
Glycerin	ml	450
"Tween 80"	ml	35
45 Syrup (sweetening)	ml	150
Distilled water to make up	ml	1000

Dissolve the phenobarbitone, β,β -methyl ethyl glutarimide and orange oil in the alcohol and "Tween 80," add the glycerin and syrup. Dissolve the tartrazine in sufficient distilled water, mix into the solution, make product up to volume with distilled water and filter. Each 5 ml. of this preparation contains 20 mgm. of phenobarbitone.

Example V

55 Multi-layer tablets for the delayed release or absorption of the drugs as indicated, were prepared consisting of the following:

Core A:	Grams
β,β -methyl ethyl glutarimide	9.2
Lactose	26.55
Icing sugar	16.8
Dextrin	2.4
65 Magnesium stearate	0.05
	55

70 The β,β -methyl ethyl glutarimide, lactose, icing sugar and dextrin are mixed thoroughly in a blender, then massed by adding a mixture of equal parts of industrial spirit and water. The moistened mass was passed through a 16 mesh and the granules dried at 50° C. The dried granules were passed through a 16 mesh then mixed with magnesium stearate. Tablets weighing 55 mgm., and con-

taining 9.2 mgm. of β,β -methyl ethyl glutarimide were so produced.

Layer B:	Grams
Phenobarbitone	65.75
Lactose	77
Gum acacia	1.5
Magnesium stearate	0.75
	145.0

The phenobarbitone and lactose were mixed thoroughly in a blender, then massed by adding gum acacia in aqueous solution. The moistened mass was passed through 16 mesh and the granules dried at 50° C. The dried granules were passed through a 16 mesh, then mixed with magnesium stearate. Layer B was compressed on Core A to form a tablet weighing 200 mgm. and containing 9.2 mgm. of β,β -methyl ethyl glutarimide and 66.75 mgm. of phenobarbitone.

Example VI

Multi-layer delayed release tablets similar to Example V were prepared consisting of the following:

Core A:	Grams
β,β -methyl ethyl glutarimide	65
Lactose	39
Icing sugar	18.2
Sodium carboxy methyl cellulose	5.2
Magnesium stearate	2.6
	130

The β,β -methyl ethyl glutarimide, lactose and icing sugar were granulated as in Example V and the dried granules passed through a 16 mesh then mixed with the sodium carboxy methyl cellulose and magnesium stearate. Tablets weighing 130 mgm. were so prepared.

Layer B:	Grams
Amylobarbitone	200
Lactose	150
Icing sugar	56
Sodium carboxy methyl cellulose	16
Magnesium stearate	8
	430

The granules were prepared as in Core A. Layer B was compressed on Core A to form a tablet weighing 560 mgm. and containing 200 mgm. amylobarbitone and 65 mgm. β,β -methyl ethyl glutarimide.

Example VII

Capsules (hard gelatine) were prepared containing the following:

	Grams
Phenobarbitone	130
β,β -methyl ethyl glutarimide	19.5
Lactose	30.25
Icing sugar	5
Dextrin	3

The β,β -methyl ethyl glutarimide, lactose, icing sugar and dextrin were granulated as in Example V. The dried granules of 16 mesh size were coated with a solution of cellulose acetate phthalate 10% w/v in acetone. The amount of coating was such that when the granules were tested in artificial intestinal juice, they disintegrated within one hour. The dried, coated granules were mixed thoroughly with the phenobarbitone and the mixture was filled into hard gelatine capsules so that each capsule contained 19.5 mgm. β,β -methyl ethyl glutarimide and 130 mgm. phenobarbitone.

Experimental work with animals and humans has been carried out employing phenobarbitone and pentobarbitone, which are the most widely used barbiturates. In all such clinical work the preparations were of the kind in

which the β,β -methyl ethyl glutarimide and barbiturate (phenobarbitone or pentobarbitone) were available simultaneously for ingestion. Results in both animals and man showed that the particular barbiturate derivatives above identified act satisfactorily. Medicinal barbiturates generally may be employed in the compositions of the invention but persons concerned with the art will appreciate that no practical advantage will accrue with those ultra-short acting barbiturates used for anaesthetic purposes only and administered by a qualified medical practitioner.

Persons concerned with the art will appreciate that the invention may also be applied in various kinds of barbiturate pharmaceutical compositions in which the barbiturate content normally constitutes a potential hazard in accidental or deliberate overdosage of barbiturate. Examples of types of compositions containing barbiturates to which the invention may thus be adapted, to the extent that risk of death from overdosage may be minimised, are as follows:

(a) Compositions comprising two or more barbiturates, such barbiturates being mixtures of short-acting, intermediate-acting, and/or long-acting drugs, e. g., mixtures of phenobarbitone and pentobarbitone. The glutarimide should be incorporated in these compositions in an amount which is the desired percentage of the total weight of the mixture of barbiturates.

(b) Compositions comprising one or more barbiturates with mild stimulants such as caffeine or amphetamine to reduce the post-barbiturate depression usually encountered as an aftermath of barbiturate administration. The glutarimide should be incorporated in an amount which is the desired percentage of the weight of the barbiturate drug or drugs in the composition.

(c) Compositions comprising one or more barbiturates with other mild sedatives as, for example, sodium bromide. The glutarimide should be incorporated in an amount which is the desired percentage of the weight of the barbiturate drug or drugs in the composition.

(d) Compositions comprising one or more barbiturates with other hypnotics as, for example, chloral or paraldehyde. The glutarimide should be incorporated in an amount as already indicated. In compositions of this kind it will be appreciated that the advantage of the glutarimide must be assessed relative to any risk of death as a result of overdose of the other hypnotic.

(e) Compositions comprising one or more barbiturates with analgesics as, for example, aspirin, phenacetin, codeine. The glutarimide should be incorporated in an amount as already indicated. In compositions of this kind it will be appreciated that the presence of the glutarimide is limited to removing the toxic effect of the barbiturate in case of overdosage. The toxic effect of the overdosage of the analgesic or analgesics remains. In practise compositions of this kind are usually such that this risk is very much less than the risk of barbiturate toxicity in the case of overdosage.

(f) Compositions comprising one or more barbiturates with antiasthmatics as, for example, ephedrine. The glutarimide should be incorporated in an amount as already indicated.

(g) Compositions comprising one or more barbiturates with anticholinergic drugs acting on autonomic effector cells as, for example, atropine. The glutarimide should be incorporated as already indicated.

(h) Compositions comprising one or more barbiturates with anticonvulsants as, for example, the hydantoin. The glutarimide should be incorporated as already indicated.

What is claimed is:

1. A pharmaceutical preparation comprising a medicinal barbiturate and a proportion of β,β -methyl ethyl glutarimide within the range of 5% to 30% by weight of the barbiturate.

2. A pharmaceutical preparation comprising a medi-

nal barbiturate and a proportion of β,β -methyl ethyl glutarimide within the range of 15% to 20% by weight of the barbiturate.

3. A pharmaceutical preparation comprising a barbiturate selected from the group consisting of phenobarbital amobarbital, butobarbitone, pentobarbital sodium, secobarbital sodium and hexobarbital sodium, and a proportion of β,β -methyl ethyl glutarimide within the range of 5% to 30% by weight of the barbiturate.

4. A pharmaceutical preparation comprising a barbiturate selected from the group consisting of phenobarbital, amobarbital, butobarbital, pentobarbital sodium, secobarbital sodium, and hexobarbital sodium, and a pro-

portion of β,β -methyl ethyl glutarimide within the range of 15% to 20% by weight of the barbiturate.
